UNITED STATES PATENT OFFICE.

HARVE R. STUART, OF SPRINGFIELD, OHIO, ASSIGNOR TO THE ROBBINS & MYERS COMPANY, OF SPRINGFIELD, OHIO, A CORPORATION OF OHIO.

FAN.

Application filed June 26, 1924. Serial No. 722,450.

To all whom it may concern:

Be it known that I, HARVE R. STUART, a citizen of the United States, residing at Springfield, in the county of Clark and State 5 of Ohio, have invented certain new and useful Improvements in Fans, of which the following is a specification.

This invention relates to improvements in fans, it relating more particularly to means 10 for adjusting the angle of the blades of the fan to direct the air currents in one direction or the other; the invention being more especially intended for fans of the type which are suspended from a ceiling for ventilation 15 purposes.

In fans of the character referred to, it is desirable and usual to provide means for changing the angle of the fan blades so as to direct the air currents either upwardly or 20 downwardly without the necessity of reversing the motor.

The object of my invention is to devise an arrangement whereby the blades may be quickly adjusted in a simple, accurate and 25 uniform manner.

Referring to the drawings:

Fig. 1 is a vertical section of the rotor of an electric motor to which the fan blades are attached, the section being on the line 30 1—1 of Fig. 2.

Fig. 2 is a top plan view of the same.

Fig. 3 is a bottom plan view of the same showing a portion of two fan blades and their shanks connected in position.

Fig. 4 is an end view of the shank of one 35 of the fan blades and its blade showing in section the rotor ring to which the shanks of the blades are attached.

Fig. 5 is an elevation of one of the blade shanks.

Referring to the drawings, 1 represents the hub of the rotor of an electric motor which is in the present case the armature. This hub is rotatably mounted upon a suitable support (not shown) and has radiating therefrom a series of downwardly and outwardly curved arms 2 to form a spider-like structure. Integrally formed with four of these arms 2 are outwardly extending radial 50 extensions 3, the outer ends of which are formed with integral heads 4 to which are attached the laminated structure 5 forming the coils of the armature.

Supported by the arms 2 is a blade carrying ring 6, this ring being preferably cast

integrally with the outer ends of these arms and lying in concentric relation with the axis of the rotor. The lower side of this ring is formed with two sets of inclined faces 7 and 8, the faces of one set being uniformly inclined at an acute angle in one direction to the plane of rotation of the ring and the faces of the other set being uniformly inclined at an acute angle in another direction to the plane of rotation of said ring, the angles of inclination, however, of both sets being of the same dimensions. The faces of one set alternate with the faces of the other set. In the structure shown in the drawings eight of these inclined faces are employed, the faces 7 being preferably marked "Up" and the faces 8 "Down." Each inclined face is provided with a pair of openings 9 to receive bolts or other suitable fastening devices for the purpose of securing 70 the blades in position. A portion 10 of two of the blades is shown in Fig. 3, each blade being connected with a curved shank 11, the outer end of each shank being formed in the nature of a flat plate 12 which is secured to 75 the inner end of the fan blade and the inner end of the shank formed with a plate 13 provided with a pair of perforations 14 to receive screw-bolts 15 or other suitable fastening devices to secure it to one of the inclined 80 faces.

If it is desired to direct the air currents downwardly the plates 13 of the blade shanks are attached to the faces 8. In the event it is desired to adjust the blades to direct the air currents upwardly the plates 13 are attached to the inclined surfaces 7. This furnishes a very simple means for quickly and accurately adjusting and changing the fan blades so as to direct the air currents 95 either upwardly or downwardly.

Having thus described my invention, I claim:

1. In a structure of the character described, a rotor, a series of spider-like arms projecting from said rotor, a ring supported by said arms in concentric relation with the axis of said rotor, the outer face of said ring being formed with a set of faces inclined in one direction with respect to the plane of rotation of said ring and with another set of faces in alternating relation with the faces of said first set and inclined in another direction with respect to the axis of rotation, and a series of fan blades adapted 100 105 110

- to be detachably connected with either set of faces.
2. In a structure of the character described, a rotor consisting of a hub, a series of spider like arms projecting from said hub, a ring supported by said arms in concentric relation with the axis of said hub, the outer face of said ring being formed with a set of faces inclined in one direction 5 with respect to the plane of rotation of said ring and with another set of faces in alter- nating relation with the faces of said first set and inclined in another direction with respect to the axis of said hub, a series of fan blades adapted to be detachably connected with either set of faces, a series of radial supports projecting beyond said ring, and armature coils carried by said supports. 15
- In testimony whereof, I have hereunto set my hand this 20th day of June 1924.

HARVE R. STUART.
